UNITED STATES PATENT OFFICE

164,835

DESK CALENDAR SUPPORT

Cecil B. Woofter, St. Paul, Minn., assignor to Brown & Bigelow, St. Paul, Minn.

Application May 17, 1951, Serial No. 15,222

Term of patent 14 years

(Cl. D74—5)

To all whom it may concern:

Be it known that I, Cecil B. Woofter, a citizen of the United States, residing in St. Paul, county of Ramsey, and State of Minnesota, have invented a new, original, and ornamental Design for a Desk Calendar Support, of which the following is a specification, reference being had to the accompanying drawings, forming part thereof:

I claim:

The ornamental design for a desk calendar support, as shown.

CECIL B. WOOFTER.
